(57) **CLAIM**

The ornamental design for a pendant, as shown and described.

DESCRIPTION

FIG. 1 is a perspective view of the pendant; FIG. 2 is a front elevational view of FIG. 1; FIG. 3 is a rear elevational view of FIG. 1; FIG. 4 is a right side elevational view of FIG. 1, the left side elevational view being a mirror image thereof; FIG. 5 is a top plan view of FIG. 1, the bottom plan view being a mirror image thereof; FIG. 6 is a perspective view of a pendant showing a second embodiment of my new design, the rear, side, top and bottom views being the same as that shown in FIGS. 3 to 5, respectively. FIG. 7 is a front elevational view of FIG. 6. FIG. 8 is a perspective view of a pendant showing a third embodiment of my new design, the rear, side, top and bottom views being the same as that in FIGS. 3 to 5, respectively. FIG. 9 is a perspective view of a pendant showing a fourth embodiment of my new design, the rear, side, top and bottom views being the same as that shown in FIGS. 3 to 5, respectively. FIG. 10 is a perspective view of a further embodiment of the pendant of FIG. 1, the rear, side, top and bottom views being shown in FIGS. 3 to 5, respectively; and, FIG. 11 is a front elevational view of FIG. 10.
